SASH AND WINDOW FRAME

Godwin H. Johnson, New York, N. Y.

Application April 10, 1934, Serial No. 719,818

2 Claims. (Cl. 20—11)

This invention relates to a sash and window frame.

The object of the invention is the production of a sash and window frame, in which the sash cords can be inspected, repaired or replaced without removing the sash from the window frame, and in which the connection between the sash cord and the sash weight can be inspected, repaired and adjusted without removing the sash from the window frame.

The second object of the invention is the production of a sash and window frame, in which the sash cords can be easily detached from its sash, while the latter is positioned in its frame and without removing the window shade, curtains, metal weather stripping and the like from the window frame.

The third object of the invention is the production of a window frame having an opening adjacent to the weather strip thereof, through which the sash cords can be repaired, replaced and the like.

The fourth object of the invention is the production of a sash with sash cords that are connected thereto and which can easily be disconnected therefrom.

In the accompanying drawing Fig. 1 indicates an inner elevation of an exemplification of my improved sash and window frame;

Fig. 2 represents an enlarged section of Fig. 1 on the line 2, 2;

Fig. 3 is a fragmentary portion of Fig. 2 with an element omitted;

Fig. 4 shows an enlarged section of Fig. 1 on the line 4, 4;

Fig. 5 represents an enlarged section of Fig. 1 on the line 5, 5;

Fig. 6 shows a section of Fig. 2 on the line 6, 6;

Fig. 7 is a section of Fig. 2 on the line 7, 7;

Fig. 8 indicates an enlarged fragmentary portion of Fig. 5;

Fig. 9 shows a section of Fig. 8 on the line 9, 9;

Fig. 10 represents a perspective view of a cover for the window frame;

Fig. 11 shows an elevation partly in section of some elements of the invention and Fig. 12 indicates a section of Fig. 11 on the line 12, 12.

The window frame in this instance is indicated having vertical members, each comprising the jamb 20 with its parting strip 21 and stop 22. The casing member is indicated at 23.

The front plates of the window frame are shown at 26 and the end plate is indicated at

27. The usual sash weight pocket is shown at 28. The upper member of the window frame is indicated at 29 and its lower member is shown at 30. Two pairs of the usual pulleys 33 are placed adjacent to the upper ends of the vertical members 26 of the window frame.

The window frame is provided with the usual upper sash 36 and the lower sash 37. The upper sash 36 comprises the stiles, 38, the upper cross member 39, the lower cross member 40 and the glass 41. The lower sash 37 comprises the stiles 45, the upper member 46, the lower member 47 and the glass 48.

Adjacent to the lower end of each jamb 20 is formed an opening 52 with the outer side 53 thereof, in this instance, in line with the inner side of the casing member 23 and its inner side 54 in line with the plane of the distant side of the parting strip 21. Each jamb 20 at the upper end of its opening 52 has formed therein the L-shaped upper rabbet having the horizontal member 55 and the vertical member 56. Each jamb 20 at the lower end of its openings 52 has formed therein the oppositely positioned lower rabbet having the horizontal member 58 and the vertical member 59. It will be noted that each of the vertical members of the rabbets cuts away a portion of the parting strip 21.

For each of the openings 52 is provided a detachable cover designed in its entirety by the numeral 60. Each cover 60 comprises the body portion 63 having a rabbet 64 at its upper end with the projecting portion 65, and the rabbet 66 at its lower end with the projecting portion 67. At one side of the body portion 63 is indicated the parting strip member 71. When the cover 60 is in operative closed position the body portion 63 and the main portion of the parting strip member 71 are located in the opening 52, with the projecting portion 65 seated in the horizontal member 55 of the upper rabbet, and the projecting portion 67 in the horizontal member 58 of the lower rabbet. At the same time the upper portion of the parting strip member 71 is located in the vertical member 56 of the upper rabbet, and the lower portion of the parting strip member 71 is located in the vertical member 59 of the lower rabbet, whereby the parting strip member 71 is positioned in alignment with the parting strip 21. Screws 73 extend through the projecting portions 65 and 67 and engage the jamb 20 to fasten the covers 60 in place.

In each of the stiles 38 of the upper sash 36, and in the stiles 45 of the lower sash 37 adjacent to the upper ends thereof, is detachably positioned an

anchor bolt 78 having the threaded shank 79 and the head 80. The axial center of the bolt 78 is preferably spaced a short distance inwardly from the center of its stile. A nut having the outer disc flange 83, and the preferably square body portion 84 is positioned in a recess at the outer face of its stile coaxial with the bolt 78 and in threaded engagement with the shank 79. A washer 86 is positioned in a recess at the inner face of the stile for the said bolt 78. Each of the stiles of the sashes has provided therefor a vertical groove 87 which extends to the upper end of the sash, and a horizontal groove 88 in each stile joins with the vertical groove 87. The anchor bolts 78 extends through the horizontal grooves 88.

A sash cord 89 in this instance a link chain, comprising links having the end portions 90, for each of the anchor bolts 78, has its lowermost link 20 encircling the bolt 78. Each of the sash cords 89 leads through one of the grooves 88 and its adjoining groove 87, and from the latter extends over one of the pulleys 33, and then leads down into its adjacent pocket 28. Sash weights are 25 indicated at 95, each having an opening 96 at its upper end. One of said sash weights is suspended from each sash cord 89. It will be noted that each sash cord passes through the openings 96 of its sash weight, and that the end link of 30 the chain as indicated at 98 is connected to another link of the chain, by inserting its end portions 90 through the end portions 90 of another link of the chain as shown in Fig. 12, and then spreading the end portions 90 of the inserted 35 link to lock it in position.

To obtain access to the sash cords 89 and their appurtenances, the user removes the covers 60 by unscrewing the screws 73. The sash cords 89 are detached from the stiles of the window sashes 40 by unscrewing the anchor bolts 78.

It will be noted that the sash cord 89, may be a rope, a piece of tape, or the like.

Various modifications may be made in the invention and the present exemplification is to be 45 taken as illustrative and limitative thereof.

Having described my invention I claim:

1. In a sash and window frame the combina-

tion of a jamb for each vertical member of the window frame forming a sash pocket therewith, each jamb having an opening, a parting strip for each jamb, sashes slidably supported in said frame at the opposite sides of said parting strip, L shaped rabbets in each jamb at the upper and lower ends of its opening, each rabbet comprising a horizontal member and a vertical member, a detachable cover for each opening, a rabbet at the upper and lower ends of each cover, a parting 10 strip member integral with each cover and projecting beyond the ends thereof, a projecting portion at the ends of each cover over the rabbet thereof, each cover when in closed position having its projecting portions seated in the horizontal members of the rabbet of the jamb adjacent thereto, the projecting portions of the parting strip member seated in the vertical members of the rabbets of the jamb and screws extending through the projecting portions of the cover and 20 secured to the jambs.

2. In a sash and window frame the combination of a jamb for the vertical members of the frame, each jamb having an opening, rabbets in said jambs at the upper and lower ends of said openings, a parting strip for each jamb extending to said rabbets, a casing member for each jamb, a stop for each jamb, a sash slidably suspended between the parting strip and the casing member, a sash slidably suspended between the parting strip and said stop, a sash weight pocket for each vertical member of the frame, each jamb having an opening with its outer side in alignment with the inner side of its casing member and the other side of the opening in alignment with the plane of the distant side of the parting strip of the jamb, a rabbet in the jamb at the upper and lower end of the opening, a detachable cover for each opening, a parting strip member integral with each cover, rabbets at the upper and lower ends of the cover engaging the rabbets in the jam and screws detachably fastening the upper and lower ends of the cover to the jamb, the parting strip member in alignment with the parting strip of the 40 jamb.

GODWIN H. JOHNSON.
